US0D1036065S

(12) United States Design Patent (10) Patent No.: US D1,036,065 S
(45) Date of Patent: * Jul. 23, 2024

(54) SHOE

(71) Applicant: BALENCIAGA, Paris (FR)

(72) Inventor: Demna Gvasalia, Paris (FR)

(73) Assignee: Balenciaga, Paris (FR)

() Term: 15 Years

(21) Appl. No.: 29/775,760

(22) Filed: Mar. 25, 2021

(30) Foreign Application Priority Data

Sep. 25, 2020 (EM) 008186043-0003

(51) LOC (14) Cl. 02-04

(52) U.S. Cl.

USPC D2/902; D2/908

(57) CLAIM

The ornamental design for a shoe, as shown and described.

DESCRIPTION

FIG. 1 is a left front perspective view of a shoe showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The portions of the shoe shown in dot-dot-dash broken lines in FIGS. 5 and 7 form no part of the claimed design. The portions of the shoe that are shown in dotted or even-dashed broken lines in FIGS. 1-6 represent thread stitching and do form a part of the claimed design.

1 Claim, 7 Drawing Sheets
